UNITED STATES PATENT OFFICE.

WILLIAM H. GATES, OF NEW HAVEN, CONNECTICUT.

COLLAPSIBLE TAP.

1,358,075.

Specification of Letters Patent.

Patented Nov. 9, 1920.

Application filed July 26, 1919. Serial No. 313,510.

To all whom it may concern:

Be it known that I, WILLIAM H. GATES, citizen of the United States, residing at New Haven, in the county of New Haven and 5 State of Connecticut, have invented certain new and useful Improvements in Collapsible Taps; and I do hereby declare the following to be a full, clear, and exact description of the invention, such as will enable others 10 skilled in the art to which it appertains, to make and use the same.

My invention relates to taps of the collapsible type, and is an improvement on the patent granted to me on December 19, 1916, 15 No. 1,209,139, and it consists in certain details of construction to be more fully set forth in the following specification.

Referring to the accompanying drawings wherein the same figures and letters of reference indicate like parts throughout the 20 several views,

Figure 1 represents a front elevation of the tap;

Fig. 2 is a sectional view of the trip shell, 25 showing the threading dies expanded with the die plate that covers the ends of the dies removed;

Fig. 3 is a broken detail view of the body of the tap with the threading dies removed;

30 Fig. 4 is a detail view of the central part of the tap showing the threading dies and die plate removed;

Fig. 5 is a broken view partly in section of the tap showing the cam rod carrying shell 35 in locked position with the threading dies removed;

Fig. 6 is an interior view of the cam rod shell and sectional view of the shank of the tap;

40 Fig. 7 is a similar view of the cam rod shell and an additional broken view of the cam rods with the shell engaged therewith;

Fig. 8 is a broken view of the tap body and sectional view of the trip shell showing 45 the cam rod actuating shell in locked position;

Fig. 9 is a broken view partly in section, and a cross sectional view of the adjustable locking bolt and trip rod;

50 Fig. 10 is a detail arrangement of the group of elements comprising the locking and tripping mechanism;

Fig. 11 is a side elevation of the cam rod shell and broken view of the shank of the tap;

55

Fig. 12 is a central sectional view of the cam rod shell and broken view of three of the cam rods engaged therewith;

Fig. 13 is a detail view of one of the 60 threading dies;

Fig. 14 is a detail view of one of the cam rods; and

Fig. 15 is a broken view of a stop located in rear of the tap.

The body of the tap, Fig. 3, comprises the 65 end 1 in which are the radial slots 2—see also Figs. 2 and 4—for the threading dies 3, common to taps of this type. The part 4 of the body is adapted to support the sliding trip shell 5. The part 5^a of the body supports the 70 sliding shell 6, and the shank 7 is adapted to enter a movable turret head—not shown. As in my former patent, the threading dies have cam grooves 8, Fig. 14, and the cam rods 9 have the cam projections 9^a engaging therewith to open and close the threading dies. 75 These cam rods have a longitudinal movement in the holes 10, Fig. 4, of the body terminating in the semi-circular recess 11, Figs. 3 and 6 of the shank.

80

The shell 6 has the central opening or bore 14, Fig. 12, and is thus slidably mounted on the shank 7 as well as on the part 5^a of the tap body. 15 are semi-circular recesses formed in the flange 16 of the shell adapted 85 to register with the semi-circular recesses 11 in the shank 7. The shell 6 is first slid along the shank until its semi-circular recesses 15 embrace the cam rods as shown in Fig. 6, then the shell is rotated—see arrow 90 a—to engage its flange 16, Figs. 7 and 12, with the notches 17 of the cam rods, and place said rods under the control of the shell. This arrangement not only enables the shell itself to engage and actuate the cam rods, instead 95 of employing an extra member for that purpose, as in my former patent, but there is no requirement for an accurate location of the shell with respect to the cam rods as was formerly the case. As soon as the flange 16 enters the notches of the cam rods, the shell is rotated until the opening 18, Figs. 6 and 7, is brought in alinement with the locking bolt 19, Fig. 3. The opening 18 may

be considerably larger than the bolt, as it simply serves as a clearance for the same. In fact, the shell has a lateral adjustment capable of its being located at any point between its semi-circular recesses 15.

5 The locking bolt, Figs. 3, 8 and 10, has the notch 20 adapted to interlock with the trip lever 21 inserted in the shell 6 and is pivoted on the pin 22. The adjusting screw 23 locates this locking bolt with respect to its proper register with the trip lever.

10 24 and 25, Figs. 3 and 4, are open recesses in the periphery of the part 4 of the body of the tap to receive the slide members 26-27—
15 see also Figs. 2 and 5—backed up by the springs 28. The slide 26 carries the trip pin 29, located in the hole 30, Fig. 4, and is adapted to lift the trip lever 21 out of its engagement with the locking bolt 19. The slide 27 carries no trip pin but serves as a steadyng feature or balance for the trip shell 5. This shell embraces the part 4 of the tap body and also a portion of the cam rod carrying shell 6. 31 are elongated recesses in the periphery of the shell 5 to admit the body of the bolts 32 adapted to engage the members 26-27, and secure them to the interior of the shell when the position of said shell is properly located with respect to the depth of a hole to be tapped.

30 The operation of the tap is as follows: After the trip shell 5 has been properly adjusted and the members 26-27 secured thereto, the threading dies are engaged, and when the predetermined depth of thread is reached, the end of the trip shell 5 will contact with the piece tapped—not shown—and be forced back and cause the pointed trip pin 29 to lift the trip lever 21 from its contact with the locking bolt, and, when thus released, the springs 33 will force the cam rod carrying shell 6 back far enough to draw the threading dies inward and thus release the thread cutting operation. The hole 30 in the shell 6 serves as a clearance for the trip pin 29. Any well known means may be employed to relock the shell 6. In Fig. 8, the handle 34 may be used for manually advancing the shell, or the stop—35, sheet 1—
40 50 may be adjustably supported on a part of the machine—not shown—so that when the tap is drawn back it will engage the shell 6 therewith, and said shell will be forced forward and relocked.

55 36 are pins, Fig. 5, carried by the members 26-27, and 37 are recesses formed in the tap body into which the pins project to prevent the said members dropping out when released from their forcible engagement with the trip shell 5. 38, Fig. 11, is a screw in the shell 6 adapted to engage the recesses 39 in the shank 7 which serves to maintain the shell in operative position.

60 The several improved features, above enumerated, not only add greatly to the service-

able value of the tap, but they also have an economical constructive value, one of which is shown in the manner of connecting the shell with the cam rods. In previous constructions, the cam rods were anchored 70 to the shell which required the holes in the shell, for the reception of the ends of the rods, to be in accurate alinement with the rods to avoid cramping. In the present arrangement, the rods are detachably connected to the shell and interlock therewith in such a manner as to leave the shell perfect freedom of adjustment with respect to its relative position with other elements of the construction.

75 Having thus described my invention, what I claim is:

1. A collapsible tap comprising a body carrying threading dies, cam rods for actuating the dies, a shell mounted to slide on the body and engage the cam rods to actuate the same, a trip lever carried by the shell, a trip shell mounted to slide on the body, an adjustable locking bolt in the body adapted to be engaged by the trip lever, said trip shell adapted to be set to regulate the tapping depth and disengage the trip lever from the locking bolt.

2. A collapsible tap comprising a body carrying threading dies, cam rods for actuating the dies, a shell mounted on the body and engaging the cam rods to actuate the same, a trip lever carried by the shell, an adjustable locking bolt in the body adapted to be engaged by the trip lever, a trip shell 95 mounted to slide on the body, said body having recesses, slide members mounted therein, a trip pin carried by one of said members, and means to secure the trip shell to said members and position the same with respect to the predetermined depth to be tapped.

3. A tap body having recesses therein, spring actuated slide members mounted therein, a trip pin carried by one of said members, a trip shell mounted to slide on the body and adapted to be adjusted thereon, and means for securing said shell to the slide members in any of its adjusted positions.

4. A collapsible tap having a body, radially operating threading dies mounted therein, cam rods, and a movable shell having an internal flange adapted to interlock with the cam rods and actuate said rods to open and close the threading dies.

115 5. A collapsible tap comprising a body having a shank, radially operating threading dies, mounted in the body, cam rods adapted to engage therewith, said body having openings therein for the reception of the cam rods, said shank having grooves therein registering with said openings, and a movable shell having an internal flange adapted to interlock with the cam rods and actuate said rods to open and close the dies.

6. A collapsible tap having a body with a projecting shank, radially operating threading dies, cam rods adapted to engage therewith, said body having openings therein for the reception of the cam rods, said rods having notches therein, said shank having grooves therein registering with the cam rod openings, and a movable shell having grooves

adapted to register with the grooves of the shank and embrace the cam rods, said shell 10 adapted to engage the notches of the cam rod and interlock therewith to actuate said rods to open and close the dies.

In testimony whereof I affix my signature.

WILLIAM H. GATES.
